UNITED STATES PATENT OFFICE

FREDERICK A. GERCICH, OF OAKLAND, AND WALTER M. BERRY, OF LOS ANGELES, CALIFORNIA, ASSIGNORS TO HAMMER-BRAY COMPANY, OF OAKLAND, CALIFORNIA, A CORPORATION OF CALIFORNIA

GAS BURNER

Application filed July 26, 1927. Serial No. 208,497.

The invention relates to a gas burner particularly designed for use in a solid-fuel fire-box of a stove.

An object of the invention is to provide a burner of the class described disposable outside a wall of a fire-box and provided with a minimum number of jet projections for extension through the wall whereby the combined area of the projection receiving openings through the wall will be a minimum.

Another object of the invention is to provide a burner of the class described having the jet openings thereof so arranged as to insure an immediate ignition at all the jets when the gas at one jet is lit.

A further object of the invention is to provide in a burner of the class described means insuring an even distribution of fuel to all the jets.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a fragmentary sectional view taken through the upper portion of a fire-box and the burner of our invention.

Figure 2 is a fragmentary plan view taken on the line 2-2 in Figure 1.

Figure 3 is a perspective view of the burner of our invention.

As herewith particularly shown, the burner 5 of our invention is operatively associated with a solid-fuel fire-box 6 having side walls 7 and 8 and an overlying cooking top 9. The cooking top overlies both the fire-box and a top-gas-burner chamber 11, it being noted that the wall 8 is common to the fire-box 6 and chamber 11. Preferably, the burner is so mounted that the major portion thereof lies without the fire-box with jet nozzles 12 extending therefrom into the fire-box 6 through openings 13 provided in the wall 8.

As here shown, the cooking top above the fire box is provided with an opening 14 in which a griddle plate 16 or the like is arranged to be disposed.

It will now be noted that burners of the class described, where mounted as shown, have heretofore been formed with a plurality of relatively close and equally spaced nozzles, thereby requiring a large number of openings in the wall through which the nozzles extend. Furthermore, to insure combustion at all the nozzles, the number of nozzles necessary to insure such distributed combustion has heretofore been such as to seriously lessen the discharge pressure at the jets and so lessen the distance to which the flame jets extend from the burner. Since the burner now described is primarily intended for heating the top plate, or griddle, above the fire-box to a cooking temperature, a relatively long flame jet is required, and hence the number of jet openings cannot be excessive, it being noted that decreasing the size of such openings, while it will increase the burner discharge pressure, will actually decrease the amount of heat generated at each jet without appreciably increasing the distance of projection of the flame jet. In accordance with our invention, however, the foregoing difficulties are overcome by grouping the jet openings at different nozzles and so directing the jets that a simultaneous burning of the gas from the different jets is insured. Accordingly, and as here shown, each nozzle 12 is provided with a pair of jet openings 17, such openings being directed slightly upwardly and angularly opposite from the axes of the nozzles whereby the flame jets projected therefrom will strike the plate 16 centrally and will at the same time substantially intersect each other. In this manner, the lighting of the gas at one jet will insure a lighting of the gas at all the other jets since a substantially continuous path of fuel is provided for the fire. And, furthermore, the jets are few enough to insure a major combustion at the plate 16 in the form of a spread flame whereby the plate will be uniformly and efficiently heated. The angular spread provided for the jets of each nozzle, it will

be noted, also insures a complete combustion of gas along the full length of the jets.

Preferably, the nozzle end faces 18 providing the jet openings 17 are perpendicular to the axes of such openings whereby drilling of the openings is facilitated and a burner of minimum weight is provided. As here shown, the two faces 18 and an imperforate face 19 together define a nozzle end of the form of a triangular pyramid.

The burner body, it will now be noted, is provided with a longitudinal passage 21 and connected branch passages 22 in the nozzles 12. The inlet end 23 of the burner is angularly related to the nozzle carrying portion of the burner whereby the gas mixer 24 at the extremity thereof may be disposed outwardly of the plane of the wall 8 when the burner is operatively disposed thereagainst. Owing to the length of the passage 21 and the fact that the gas is supplied thereto at an end, it has been found that the nozzles closest to the mixer tend to receive too little gas owing to a certain suction effect produced by the gas passing them as it moves toward the other jets. The effect is overcome somewhat by reason of the provision of the nozzle passages 22 which extend transversely from the passage 21 for supplying the pair of jet openings at the nozzle ends. To still further insure an even distribution of gas from the passage 21, a baffle 25 is provided in the passage ahead of and adjacent the first nozzle, such baffle extending into the passage from the nozzle side thereof whereby a direct sweep of gas across the mouth of the first nozzle passage 22 is positively prevented, and is minimized somewhat at least the second nozzle passage 22. In this manner it has been found that the gas pressure at the different jet openings is the same, so that a uniform distribution of the fuel is effected along the length of the fire-box and an even heating of the plate 16 is effected.

We claim:

1. In combination with a fire-box having a cooking plate thereover, a burner operatively disposed outside of said fire-box and provided with a plurality of parallelly aligned integral jet nozzles extending into said fire-box in a common horizontal plane, each of said nozzles being provided with a plurality of jet openings, the various jet openings being in coplanar relation and inclined upward towards said plate, the axes of the jets of adjacent openings of adjacent nozzles intersecting.

2. In combination with a solid fuel fire-box having a cooking plate thereover, a gas burner arranged to discharge intersecting jets of flame obliquely upwardly against said plate in coplanar relation with each other, said jets of flame being discharged from substantially spaced apart parallel jet nozzles

disposed in a substantially horizontal plane and formed integral with said burner.

In testimony whereof, we have hereunto set our hands at Oakland, California, and Los Angeles, California, respectively.

FREDERICK A. GERCICH.
WALTER M. BERRY.
